UNITED STATES PATENT OFFICE.

PIETER DE LANGE AND ROBERT AERNOUT BARON VAN LYNDEN, OF UTRECHT, NETHERLANDS, ASSIGNEES TO NAAMLOOZE VENNOOTSCHAP DE NEDERLANDSCHE THERMO-TELEFOON MAATSCHAPPIJ, OF UTRECHT, NETHERLANDS, A CORPORATION OF NETHERLANDS.

THERMIC TELEPHONE.

1,245,575.

Specification of Letters Patent.

Patented Nov. 6, 1917.

Application filed November 4, 1915. Serial No. 59,628.

To all whom it may concern:

Be it known that we, PIETER DE LANGE and ROBERT AERNOUT BARON VAN LYNDEN, both subjects of the Queen of the Netherlands, and residing at Utrecht, in the Netherlands, have invented a new and useful Thermic Telephone, of which the following is a specification.

Our invention relates to thermic telephones in which the sound is reproduced by means of a heating conductor. The object of our invention is to provide means through which the heating conductor is enabled to stand a comparatively strong load or temporarily even an overload, without burning out owing to overheating. This object we accomplish by arranging a heat discharging body in contact with the exposed sound producing portion of the heating conductor. When the heating conductor is of some length, this heat discharging body may simultaneously be utilized to serve as a support for it and protect it against the damaging influence of vibrations and the like. Inasmuch as it is rendered possible to overload the heating conductor without danger of burning it out an improved reproduction of sound is attained as compared with what would be attainable with the same apparatus but without a heat discharge.

Reference is to be had to the accompanying drawings in which we have illustrated by way of example, an embodiment of our invention. Figure 1 shows a thermic telephone in elevation, partly in section, drawn to an enlarged scale, Fig. 2 is a detail view of the support for the heating conductors.

The telephone shown is designed to be directly introduced into the auditory passage of the human ear. It comprises a tubular casing 1 provided with a sound opening 2 at the top and closed by a plug 3 screwed into a thread 4 at its bottom. In the illustrated example, the heating conductor consists of an arched heating wire, the exposed portion 5 of which serves as sound emitter. Its branches 7 are fixed in a support 6 of insulating material, and connected to the current conductors 8 and 9. The heating conductor 5, 7 and its support 6 are covered by a cap 10, the interior 11

of which forms the sounding chamber and communicates through an opening 12 at its top with the sound opening 2 of the casing 1. The upper part of cap 10 abuts against an annular flange 13 of casing 1, while its base abuts against a flange 14 provided on the heating conductor support 6. The support 6 and the cap 10 are secured in place within the casing 1 by means of the screw 60 plug 3 which presses against the support 6.

The heat discharge body 15, according to our invention, is in contact with the exposed portion 5 of the heating conductor. It must possess sufficient heat capacity to effectively cool the wire 5, 7 when it becomes heated by current passing through it. On the other hand, there must be no danger of short circuiting by the discharger. The heat discharger 15 is either made of a semi-conductor, such as marble; or of a conductor such as metal, coated with a layer of insulating material.

In the example illustrated, the heat discharger 15 rests upon two studs 16 on which it is held by screw nuts 17. The studs 16 are fixed to the heat conductor support 6. As the discharger 15 is able to receive comparatively great amounts of heat and, owing to its large area, to discharge them rapidly, a continuous and efficient cooling action on the heating conductor is secured even with considerable loads of comparatively long duration.

With a heating conductor consisting of a plurality of heating wires, the cooling may be effected either by means of a single heat discharger common to all the heating wires, or by means of a plurality of heat dischargers, the number, shape, and manner of arrangement of which has no bearing on the scope of our invention.

We have found by tests that the action of a heating conductor co-operating with a discharger in contact with its sound emitting portion is not affected as compared with the action of a heating conductor without a discharger. It follows that our heat discharging device has no unfavorable influence whatever on the operation of the telephone.

It is obvious that our invention is not limited to the precise structure illustrated,

in which various modifications may be made without thereby involving any departure from our invention.

We claim:

- 5 1. In a thermic telephone, the combination of a heating conductor with a heat dis-
-charger in contact with the sound emitting
portion of said heating conductor.
- 10 2. In a thermic telephone, the combina-
tion of a heating conductor, a heating con-
ductor support, and a heat discharger, said
heat discharger being secured upon said
support in a position in which said heat
discharger contacts with the sound emitting
15 portion of said heating conductor.
- 15 2. In a thermic telephone, the combina-
tion of a heating conductor, a heating con-
ductor support, a pair of studs mounted
upon said support, and a heat discharging
20 body secured upon said studs so as to be in
contact with the sound emitting portion of
said heating conductor.
- 20 4. In a thermic telephone, the combina-
-

tion of a heating conductor with a heat dis-
charging body made of a semi-conductor, 25
said heat discharging body being held in
contact with the sound emitting portion of
said heating conductor.

5. A thermic telephone, comprising in
combination, a heating conductor, a sup- 30
port for said heating conductor, a heat dis-
charger held in contact with the sound
emitting portion of said heating conductor,
means for supporting said heat discharger
upon said support for said heating conduc- 35
tor, and a mounting for said latter support.

6. A thermic telephone comprising a heat-
ing conductor and a heat-discharging body
having a non-conducting surface in contact
with the sound-emitting portion of said 40
heating conductor.

In testimony whereof, we have signed this
specification.

PIETER DE LANGE.

ROBERT AERNOUT BARON VAN LYNDEN.
